VARIABLE CAPACITY PUMP

Hugo Centervall, Brooklyn, N. Y., assignor to
 Manly Corporation, New York, N. Y., a corporation of Delaware

Application March 24, 1932, Serial No. 600,914

21 Claims. (Cl. 103—161)

This invention relates to improvements in pumps or fluid motors of the type having rotating radial cylinders and a non-rotatable valve member.

5 The principal object of the invention is to provide an improved pump or motor of this type that is simple, relatively inexpensive to manufacture, compact and easy to assemble and disassemble.

The improvements constituting the invention 10 are particularly useful in pumps and motors of variable capacity such as are used for power transmission for accurate speed control or to obtain variable torque, but may be employed with advantage in pumps and motors of fixed capacity.

15 Other and more specific objects will appear from the following description of an illustrative embodiment of the present invention.

In the drawings:

Figure 1 is a transverse view, partly in section, 20 of a pump or motor constructed in accordance with the present invention and taken along the line 1—1 of Figure 2.

Fig. 2 is a central longitudinal view along the line 2—2 of Fig. 1;

25 Fig. 3 is a transverse sectional view along the line 3—3 of Fig. 2;

Fig. 4 is an elevation of one of the connecting rod members as viewed lengthwise of the device;

Fig. 5 is an elevation of one of the connecting 30 rod members as viewed transversely of the device;

Fig. 6 is a top plan view of one of the connecting rod members; and

35 Figs. 7 and 8 are fragmentary sectional views showing alternative embodiments of portions of the connecting rod member.

Before explaining the present invention, it is to be understood that the invention is not limited in its application to the details of construction 40 and arrangement of parts described herein and illustrated in the accompanying drawings, since the invention is capable of other embodiments and of being practiced and carried out in various ways. It is also to be understood that the phraseology or terminology used herein is for the purpose of description and not for limitation, and it is not intended to limit the invention beyond the terms of the several claims hereto appended as considered in view of the prior art 45 and the requirements thereof.

50 Referring now to the drawings, 9 indicates the enclosing casing which is preferably formed in two portions and as here shown comprises a rear member 11 to which is securely attached a front member 12, the two members being held

together by bolts 13. The enclosing casing forms the support for the device and the member 11 is accordingly provided with feet 14. Both of the members 11 and 12 are provided with fins or ribs 15 to facilitate radiation.

5 The rear member 11 is formed with a hub 16 whose preferably tapered bore is adapted to receive one end of the stationary cylindrical valve member 20 which is keyed against rotation by a cap screw 17, as shown in Figure 3. The valve 10 member 20 is held in place lengthwise of the hub 16 by nuts 19, as indicated in dotted lines in Fig. 2 on the outer ends of the threaded studs 18 which pass through suitable openings in the rear cover plate 10 and whose inner ends are 15 secured in the valve member 20. (Fig. 3).

For the purpose of this description the structure will be considered as a pump.

The valve member 20 is provided with the usual 20 valve ports 21 and 22 which are separated by a transverse land 23. Longitudinal passages 25 and 26 lead from the valve ports 21 and 22 respectively and extend lengthwise in the valve member 20 from said valve ports through its rear end in the hub 16 of the member 11. The 25 rear cover plate 10 is likewise formed with two passages 27 and 28 adapted to register with the passages 25 and 26, respectively, and to the outer ends of said passages 27 and 28 are attached appropriate pipe connections 29 and 30, respectively. With the parts in the position shown in the drawings and rotating to the right, or clockwise, as shown in Fig. 1, the port 21 constitutes 30 the suction and the port 22 the pressure port.

35 The cylinder body 31 is rotatably mounted upon the valve member 20 and for this purpose is provided with a central bore 32, the fit of the parts being such as to permit the cylinder body 31 to rotate freely while forming a substantially fluid tight running joint. To the cylinder body 31 is attached by pins 33 and cap screws 34 a flange 35 on one end of the revoluble shaft 36 which passes through an appropriate opening in the front casing member 12, suitable packing 37 being used to prevent leakage. The shaft 36 constitutes 40 the driving shaft in case the apparatus is used as a pump and the driven shaft when used as a motor. The cylinder body 31 is provided with a plurality of radially disposed cylinders 38 having ports 39 on their inner ends adapted to register 45 with the valve ports 21 and 22 in the valve member 20, said ports 39 being preferably less in area than the area of the cylinders 38. The cylinder body 31 is preferably formed of one solid body 50 and the number of cylinders is preferably five, 55

although this number may be more or less, as desired.

Slidable within the cylinders 38 are pistons 40, here shown as hollow, which are provided with 5 piston pins 41 extending through slots 42 in the outer ends of the walls of said cylinders 38 and positioned substantially parallel with the axis of rotation of the cylinder body 31. The pistons 40 and the piston pins 41 are held together by pins 10 43, preferably made of bronze, which are kept in place by the walls of the cylinders 38, the proportions of the parts being such that the pins 43 are within the bore of the cylinders 38 at all points of the stroke of the pistons 40.

15 For each piston 40 there is provided a connecting rod member 45 which is preferably made of bronze, although other materials or a combination of materials may obviously be used if preferred. This connecting rod member 45 which constitutes 20 one of the novel and important features of my improved structure is shown in detail in Figs. 4, 5 and 6. In the present embodiment the connecting rod member 45 consists primarily of a sleeve 46, of generally elliptical cross section, 25 which surrounds the cylinder with its longer diameter transverse to the axis of rotation to allow a limited rocking motion of the member 45 with respect to the cylinder. Projecting axially at the inner face of each sleeve 46 are shoes 48 of 30 arcuate configuration and with their outer faces curved to fit within the inner faces of the inner races 56 of the bearing assemblies 57. The shorter diameter of the elliptical sleeves 46 corresponds with the outer diameter of the cylinders 38 and 35 each sleeve is fitted to its cylinder so as to have a freely sliding contact with the wall of the cylinder or with a face formed on its outer wall. The outer ends of the sleeves 46 are provided at the sides with hubs 47 bored to receive the 40 ends of the piston pin 41.

The shoes 48 are held in place with respect to said inner circumferential surfaces of the races 56 by retainer rings 51 which are received within 45 segmental channels 49 formed in the inner faces of the ends of the shoes 48 which preferably project outwardly beyond the said races 56. In order to secure compactness, the ends of the piston pins and the hubs 47 are cut away flush with the outer surface of the tubular member 50 46 to a point slightly beyond the middle of the pins to permit them to clear the slideways 61 which will be described later. This cutting away does not reduce the useful bearing surface for the reason that the pressure is outward on the 55 pistons and hence the inner sides of said piston pins 41 and said hubs 47 are never subject to heavy pressures. The arrangement is such that the piston pins 41 may turn freely in the hubs 47 and the shoes 48 may slide upon the inner circumferential surfaces of the races 56 so that the connecting rod member 45 may properly adjust 60 itself to compensate for its varying angularity with respect to the cylinder 38 and the piston 40 during the stroke of said piston 40.

65 In operation, the races 56 rotate substantially with the piston assembly so that the only movement of the shoes 48 relative to the races 56 is the slight amount necessary to compensate for angularity of the connecting rod member 45, and 70 as the races 56 and the shoes 48 are positioned relatively near the center of rotation, this relative movement is very small. While the connecting rod member 45 has been shown herein as integrally formed, it will be obvious that it may be 75 made in properly connected sections if desired.

While oil vapor (as oil is the fluid usually employed) within the enclosing casing will ordinarily furnish sufficient lubrication for the shoes 48, there is provided additional lubricating means for this purpose. The inner faces of the shoes 48 are recessed to form pockets 52 connected by passages 53 with the outer faces of said shoes 48 which bear against the inner circumferential surfaces of the races 56. The end of the cylinder body 31 adjacent the hub 16 of the casing member 11 10 is cut away to form a taper 54 and the end of said cylinder body 31 adjacent the flange 35 is provided with a plurality of angularly drilled holes 55 leading from the space between the end of the valve member 20 and the said flange 35. 15 Fluid leaking out of the valve ports 21 and 22 and the cylinder ports 39 will pass out toward the ends of the bore 32 of the cylinder body 31 and the arrangement is such that centrifugal force produced by the rotating cylinder body 31 will 20 cause such leakage fluid to be thrown, by the taper 54 and the angular holes 55, into the pockets 53 whence it will pass through the passages 53 to the outer faces of the shoes 48 and the inner circumferential surfaces of the races 56. 25

Each bearing assembly 57 is carried by a laterally movable slide 60 which is formed to receive the outer race 58. Each slide 60 is supported upon parallel transverse slideways 61, one such pair of slideways 61 being formed in the inner side 30 of the casing member 12 and another such pair being formed in the opposing inner side of the casing member 11. The slideways 61 are partially cut away in the middle, as shown in Fig. 1, to provide clearance for the rotating cylinder and 35 piston assemblies in a device of compact design. The two slides 60 are fastened together in order to secure uniformity of their movement and position, and for this purpose each slide 60 is provided on both its ends with guide studs 62 which project through suitable openings in covers 63 which close appropriate openings in the sides of the casing member 11. The outer ends of the guide studs 62 pass through holes in the cross-heads 64 and are held in place with respect to it and 45 with respect to each other by means of nuts 65 in cooperation with shoulders 66 formed on said guide studs 62. The inner surfaces of the covers 63 form stops for the reduced ends 67 of the slides 60, as shown in Fig. 1. Lateral movement of the 50 slides 60 may be effected by any preferred means, such as an appropriate screw and nut device, not shown, but which is connected to one of the cross-heads by a stud 68.

The position of the inner races 56 of the bearing assemblies 57 determines the length of the stroke of the pistons 40 and the direction of flow of the fluid. Hence, by movement of the slides 60 the stroke of the pistons 40 may be infinitely varied at will from zero (when the slides 60 are 60 in their middle position and the axis of rotation of the cylinder body 31 and the centers of the races 56 are coincident) to maximum (when the slides 60 are in their extreme outward positions). The direction of flow of the fluid may obviously 65 be reversed by moving the slides 60 from one side to the other of their middle or zero stroke position.

Where a fixed stroke of the pistons is desired, it will be obvious that the bearing assemblies 57 may be carried upon any suitable non-movable 70 supports such as annular recesses formed in the casing member 12 and in the rear wall of the casing member 11 and adapted to receive the outer races 58.

An alternative design of the shoes 48 of the 75

Connecting rod member 45 and their associated parts is shown in Fig. 7. In this embodiment a ring 70 is fitted within each race 56 in such a manner that its inner edge projects beyond the inner face of said race 56. The shoes 48 are slidably disposed against the inner circumferential surface of this ring 70 and the sides 46 are modified to contain segmental grooves 71 which receive the inner edge of the ring 70 which functions as a retainer ring. The rings 70 are preferably made of such width and so positioned that their outer edges project beyond the outer faces of the races 56 an amount equal to the already described inward projections in order that there may be substantially equal bearing surface on each side of the center of each of the bearing assemblies 57.

Fig. 8 shows a second alternative embodiment of this part of the device. In this instance the side walls of the connecting rod member 46 are formed with outwardly projecting segmental flanges 73 which are received within annular channels 74 recessed in the inner or opposing faces of the inner races 56 of each of the bearing assemblies 57. The channels 74 cause the bearing races 56 to act as retainer rings and prevent the inward radial movement of the connecting rod members 45, thus maintaining the shoes 48 in proper position with respect to the races 56.

The operation of the device will be readily understood. The cylinder member 31 with the radial cylinders 38 rotates about the stationary valve member 20 as a center while the connecting rod members 45 rotate around the center of the bearing assembly 57; hence if the slides 60 are adjusted to displace the bearings out of exact concentric relation with the valve member the pistons 40 and connecting rod members 45 will be reciprocated radially of the cylinders, thereby drawing the oil or other liquid into the cylinders on the outward movement of the pistons and expelling the oil on the inward movement. The stationary valve member 20, as shown in Fig. 1, is cut away on its upper side sufficiently for all the cylinders to be connected to the common intake port 21 during the outward movement of the pistons, and is similarly cut away on its lower side to thereby connect all the cylinders to the common delivery port 22 on the inward movement of the pistons, assuming the direction of rotation and adjustment of the parts to be as indicated. If the slides 60 are adjusted toward the left as shown in Fig. 1, to shift the center of rotation of the bearing assembly 57 to the left of the center of the valve member 20, the pistons will obviously move inwardly instead of outwardly while the cylinders are in fluid-transmitting connection with the port 21, thus connecting that port into the discharge port of the pump and the port 22 into the suction port. If the pump is used as a source of fluid under pressure for operating an hydraulic motor this reversal of the direction of flow of liquid in the ports 21 and 22 will serve to reverse the direction of rotation of the motor shaft. Also the extent to which the bearing assembly 57 is adjusted out of concentric relation with the valve member 20 determines the length of the piston stroke and consequently the capacity of the pump and the speed and torque of the hydraulic motor as described, for example, in the patent of Chas. M. Manly, No. 1,266,606, granted May 21, 1918.

The pump or motor of this application is primarily an improvement over the pump and motor described in the Manly patent. Its prin-

pal advantages are the greater simplicity of design with an elimination of a great many parts. The design is particularly adapted for ease of assembly. In assembling the pump the pistons with their connecting rod members connected thereto are placed in their cylinders. The rings 51 are then mounted in the grooves in the inner faces of the shoes 48. The previously assembled ball bearings are then assembled over the shoes 48, thus connecting all the connecting rod members together into a single unit. The assembly unit is then slipped over the valve member and the outer race of the bearing adjacent the hub 16 fitted into its slide 60, or the slide may be fitted over the bearing before the assembly is mounted on the stationary valve member and the slide fitted into its slideway when the cylinder block is pushed back of the valve member to bring the ports 39 of the cylinders into alignment with the ports 21 and 22 of the valve body.

The outer slide 60 will then be assembled on the outer bearing assembly and when the cover 12 is fastened in place the parts will be maintained in their assembled position.

One particular advantage of the present construction is the elimination of substantially all sliding friction between parts whose surfaces are under pressure. The pressure on the stationary valve member is substantially balanced by the pressure in the cylinders due to the ports 39 being of less area than the ends of the cylinders. Hence the only friction between plain bearings on parts under pressure is the friction incidental to the rocking movement of the connecting rod members and, as will be observed from Fig. 1 of the drawings, this movement is of such slight extent as to be practically negligible.

By the arrangement of the two main bearings symmetrical with respect to the plane of the centers of the cylinder, all torsional strains are eliminated. Also, as the connecting rod members and bearings are external to the cylinder assembly, they may be as large and rugged as necessary to readily transmit the load to which they are to be subjected.

I claim:

1. In a pump or motor, the combination of a rotating cylinder structure having a plurality of radial cylinders, pistons therein, a sleeve member surrounding each cylinder pivotally connected to the outer end of the piston thereof, a member rotatable about an axis eccentric with respect to the axis of rotation of the cylinder body, and means connecting said sleeve members to said rotating member for rotating movement therewith and relative circumferential movement with respect thereto.

2. In a pump or motor of the class described, the combination of a rotating cylinder member having rotating cylinders, pistons therein, and means for reciprocating said pistons upon the rotation of said cylinder member, said means comprising connecting rods pivotally connected to the outer ends of said pistons, said connecting rods consisting of sleeve members surrounding said cylinders and having axially projecting shoes, a rotating ring surrounding said shoes, and a bearing eccentric to the axis of rotation of said cylinder member in which said ring is rotatably mounted.

3. In a pump or motor of the class described, the combination of a stationary valve member, a cylinder body having radial cylinders rotatably mounted on said valve member, pistons mounted in said cylinders, connecting rod members piv-

- totally attached to the outer ends of said cylinders, said members comprising sleeves surrounding said cylinders, the diameter of said sleeves in the plane of rotation being sufficient to permit 5 oscillation of said members with respect to the cylinders, shoes projecting axially from one side of said sleeves, the outer faces of said shoes being shaped to a common curvature, a rotating ring surrounding said shoes, means for holding said 10 shoes in sliding contact with the inner circumference of said ring, and a bearing eccentric to the axis of rotation of said cylinders for supporting said ring.
4. In a pump or motor, a non-rotatable valve member having ports for the passage of fluid, a 15 rotatable cylinder body having a plurality of radially arranged cylinders, ports in said cylinders adapted to register with said valve ports, pistons in said cylinders, a plurality of freely 20 rotatable rings and a connecting rod member for each piston, said connecting rod member comprising a plurality of portions radially disposed with respect to said rings, the outer ends of which are operatively connected with said piston 25 and the inner ends of which are operatively connected with said rings, and means rigidly connecting said radially disposed portions.
5. In a pump or motor, a non-rotatable valve member having ports for the passage of fluid, a 30 rotatable cylinder body having a plurality of radially arranged cylinders, ports in said cylinders adapted to register with said valve ports, pistons in said cylinders, a plurality of freely 35 rotatable rings, and a connecting rod member for each piston, said connecting rod member comprising a plurality of portions radially disposed with respect to said rings, one of the ends of which are rockably connected with said piston and the other ends of which are adapted to 40 form shoes slidably bearing against said rings without definite attachment thereto, and means rigidly connecting said radially disposed portions.
6. In a pump or motor, a central cylindrical non-rotatable valve member having ports for 45 the passage of fluid, a rotatable cylinder body having a plurality of radially arranged cylinders, ports in said cylinders adapted to register with said valve ports, pistons in said cylinders, a plurality of rings positioned eccentrically with respect to the axis of rotation of said cylinder body, and a connecting rod member for each piston, said connecting rod member comprising a plurality of portions radially disposed with respect to said rings, one of the ends of which are 50 rockably connected with said piston and the other ends of which are adapted to bear against the inner side faces and inner circumferential surfaces of said rings without definite attachment thereto, and means rigidly connecting said radially 55 disposed portions.
7. In a pump or motor, a non-rotatable valve member having ports for the passage of fluid, a rotatable cylinder body having a plurality of radially arranged cylinders, ports in said cylinders adapted to register with said valve ports, pistons in said cylinders, a plurality of freely rotatable rings, a connecting rod member for each piston, said connecting rod member comprising a plurality of rigidly joined portions radially disposed with respect to said rings, the outer ends of which are operatively connected with said piston and the inner ends of which are operatively connected with said rings but without definite 60 attachment thereto, and means for continuously 65
- maintaining said connecting rod member in proper relation to said rings.
8. In a pump or motor, a non-rotatable valve member having ports for the passage of fluid, a rotatable cylinder body having a plurality of radially arranged cylinders, ports in said cylinders adapted to register with said valve ports, pistons in said cylinders, a plurality of movably supported rings, means for moving said rings to vary their centers with respect to the center of rotation of said cylinder body and a connecting rod member for each piston, said connecting rod member comprising a plurality of portions radially disposed with respect to said rings, the outer ends of which are operatively connected with said piston and the inner ends of which are operatively connected with said rings, and means rigidly connecting said radially disposed portions. 10
9. In a pump or motor, a non-rotatable valve member having ports for the passage of fluid, a 15 rotatable body having a plurality of radially arranged cylinders, ports in said cylinders adapted to register with said valve ports, pistons in said cylinders, a plurality of movably supported rings, means for moving said rings to vary their centers with respect to the center of rotation of said cylinder body, and a connecting rod member for each piston, said connecting rod member comprising a plurality of portions radially disposed with respect to said rings, one of the ends of which are rockably connected with said piston and the other ends of which are adapted to 20 form shoes slidably bearing against said rings without definite attachment thereto, and means rigidly connecting said radially disposed portions. 25
10. In a pump or motor, a non-rotatable valve member having ports for the passage of fluid, a rotatable cylinder body having a plurality of radially arranged cylinders, ports in said cylinders adapted to register with said valve ports, pistons in said cylinders, a plurality of movably supported rings, means for moving said rings to vary their centers with respect to the center of rotation of said cylinder body, a connecting rod member for each piston, said connecting rod member comprising a plurality of portions radially disposed with respect to said rings, the outer ends of which are operatively connected with said piston and the inner ends of which are operatively connected with said rings but without definite attachment thereto, and means continuously maintaining said connecting rod members in proper relation to said rings. 30
11. In a pump or motor, a central cylindrical non-rotatable valve member having ports for the 35 passage of fluid, a rotatable cylinder body having a plurality of radially arranged cylinders, ports in said cylinders adapted to register with said valve ports, pistons in said cylinders, a plurality of movably supported rings, means for moving said rings to vary their centers with respect to the center of rotation of said cylinder body, a connecting rod member for each piston, said connecting rod member comprising a plurality of rigidly joined portions radially disposed with respect to said rings, the outer ends of which are rockably connected with said piston and the inner ends of which are adapted to bear against the inner side faces and the inner circumferential surfaces of said rings without definite attachment thereto and means continuously maintaining said connecting rod members in proper relation to said rings. 40
12. In a pump or motor, a central cylindrical 45

- non-rotatable valve member having ports for the passage of fluid, a rotatable cylinder body having a plurality of radially arranged cylinders, ports in said cylinders adapted to register with said valve ports, pistons in said cylinders, a pair of bearing assemblies having inner and outer races and positioned eccentrically with respect to the center of rotation of said cylinder body, a connecting rod member for each piston, said connecting rod member comprising a pair of rigidly joined portions radially disposed with respect to said bearing assemblies whose outer ends are rockably connected with said piston and whose inner ends are adapted to form segmental shoes slidably bearing against the inner circumferential surfaces of said inner races without definite attachment thereto, and means continuously maintaining said shoes in proper position with respect to said inner races.
13. In a pump or motor, a central cylindrical non-rotatable valve member having ports for the passage of fluid, a rotatable cylinder body having a plurality of radially arranged cylinders, ports in said cylinders adapted to register with said valve ports, pistons in said cylinders, a pair of movably supported bearing assemblies having inner and outer races, means for moving said bearing assemblies to vary their centers with respect to the center of rotation of said cylinder body, a connecting rod member for each piston, said connecting rod member comprising a pair of rigidly joined portions radially disposed with respect to said bearing assemblies whose outer ends are rockably connected with said piston and whose inner ends are adapted to form segmental shoes slidably bearing against the inner circumferential surfaces of said inner races without definite attachment thereto, and means continuously maintaining said shoes in proper position with respect to said inner races.
14. In a pump or motor, a central cylindrical non-rotatable valve member having ports for the passage of fluid, a rotatable cylinder body having a plurality of radially disposed cylinders, ports in said cylinders adapted to register with said valve ports, pistons in said cylinders, a plurality of rings eccentrically positionable with respect to the axis of rotation of said cylinder body, means for varying the centers of said rings with respect to the axis of rotation of said cylinder body, and a connecting rod member for each piston operatively connecting said piston with said rings, said connecting rod member comprising a plurality of rigidly joined portions radially disposed with respect to said rings whose outer ends are rockably connected with said piston and whose inner ends are adapted to slidably cooperate with said rings, but without definite attachment to said rings, in such a manner as to substantially prevent lengthwise and outwardly radial movement of said connecting rod member with respect to said rings.
15. In a pump or motor, a central cylindrical non-rotatable valve member having ports for the passage of fluid, a rotatable cylinder body having a plurality of radially disposed cylinders, ports in said cylinders adapted to register with said valve ports, pistons in said cylinders, a plurality of rings eccentrically positionable with respect to the axis of rotation of said cylinder body, means for varying the centers of said rings with respect to the axis of rotation of said cylinder body, a connecting rod member for each piston operatively connecting said piston with said rings, said connecting rod member comprising a pair of rigidly joined portions radially disposed with respect to said bearing assemblies whose outer ends are rockably connected with said piston and whose inner ends are adapted to form segmental shoes slidably bearing against the inner circumferential surfaces of said inner races without definite attachment thereto, and means continuously maintaining said shoes in proper position with respect to said inner races.
16. In a pump or motor, a cylindrical valve member having ports for the passage of fluid, a rotatable cylinder body having a plurality of radially arranged cylinders, ports in said cylinders adapted to register with said valve ports, pistons in said cylinders, a plurality of rings rotatable in company with said pistons, a connecting rod member for each piston comprising a plurality of rigidly joined portions radially disposed with respect to said rings and whose outer ends are operatively connected with said pistons and whose inner ends are adapted to form shoes slidably bearing against the inner circumferential surfaces of said rings, and means for lubricating the bearing surfaces of said rings, said lubricating means comprising passages from the outer to the inner faces of said shoes, pockets in the inner faces of said shoes communicating with said passages, and means whereby fluid leaking out of said valve ports and said cylinder ports is supplied to said pockets by centrifugal force produced by the rotating parts.
17. In a pump or motor, a cylindrical valve member having ports for the passage of fluid, a rotatable cylinder body having a plurality of radially arranged cylinders, ports in said cylinders adapted to register with said valve ports, pistons in said cylinders, a plurality of bearing assemblies having inner and outer races, an annular channel in the inner face of the inner race of each of said bearing assemblies, and a connecting rod member for each piston operatively connecting said piston with said bearing assemblies, said connecting rod member including a plurality of rigidly joined portions radially disposed with respect to said bearing assemblies and said radially disposed portions having segmental flanges adapted to be received within said annular channels in said inner races of said bearing assemblies.
18. In a pump or motor, a cylindrical valve member having ports for the passage of fluid, a rotatable cylinder body having a plurality of radially arranged cylinders, ports in said cylinders adapted to register with said valve ports, pistons in said cylinders, a plurality of bearing assemblies having inner and outer races, a ring within each of said inner races of greater width than said races and projecting inwardly toward said cylinder body, and a connecting rod member for each piston operatively connecting said piston and said rings, said connecting rod member including a plurality of rigidly joined portions radially disposed with respect to said rings and having segmental channels adapted to receive said rings.
19. In a pump or motor, a cylindrical member having ports for the passage of fluid, a rotatable cylinder body having a plurality of radially arranged cylinders, ports in said cylinders adapted to register with said valve ports, pistons in said cylinders, a plurality of rings rotatable in company with said pistons, a plurality of retainer

- rings, and a connecting rod member for each piston, said connecting rod member including a plurality of rigidly joined portions radially disposed with respect to said first named rings whose 5 outer ends are operatively connected with said piston and whose inner ends are adapted to form shoes slidably bearing against the inner circumferential surfaces of said first named rings, said shoes having segmental channels for receiving 10 said retainer rings.
20. In a pump or motor, the combination of a rotating cylinder structure having a plurality of radial cylinders, pistons therein, a pair of connecting rod members disposed on opposite sides 15 of each cylinder each comprising a body portion, two end portions and means at least in part interposed between adjacent cylinders for rigidly connecting said body portions, means for pivotally connecting the outer end portions of each pair 20 of said connecting rod members to the outer end of one of said pistons, a member rotatable about an axis eccentric with respect to the axis of rotation of the cylinder structure, and means con-

necting the inner end portions of each pair of connecting rod members to said rotatable member for rotating movement therewith and relative circumferential movement with respect thereto.

21. In a pump or motor, the combination of a 5 rotating cylinder structure having a plurality of radial cylinders, pistons therein, a pair of connecting rod members disposed on opposite sides of each cylinder each comprising a body portion, two end portions and a connecting member disposed inwardly of the end portions rigidly connecting said body portions, means for pivotally connecting the outer end portions of each pair of 10 said connecting rod members to the outer end of one of said pistons, a member rotatable about an axis eccentric with respect to the axis of rotation of the cylinder structure, and means connecting the inner end portions of each pair of 15 connecting rod members to said rotatable member for rotating movement therewith and relative 20 circumferential movement with respect thereto.

HUGO CENTERVALL.
